UNITED STATES PATENT OFFICE.

MARSHALL H. FARNSWORTH, OF BROOKLYN, ASSIGNOR TO THE OHIO WOODEN WARE MANUFACTURING COMPANY, OF CLEVELAND, OHIO.

METALLIC WASH-BOARD PLATE.

SPECIFICATION forming part of Letters Patent No. 258,396, dated May 23, 1882.

Application filed October 8, 1881. (Model.)

To all whom it may concern:

Be it known that I, MARSHALL H. FARNSWORTH, of Brooklyn village, in the county of Cuyahoga and State of Ohio, have invented 5 a certain new and Improved Metallic Wash-Board Plate; and I do hereby declare that the following is a full, clear, and complete description thereof.

My improvement relates to a metallic plate 10 for wash-boards; and it consists in the construction of the plate with a series of peculiarly-formed corrugations with angular swells and depressions alternating upon the said corrugations, the angles being in opposite directions to each other obliquely across the plate.

For a fuller and more complete description of the said plate reference will be had to the following specification and to the annexed drawings, making a part of the same, in which—

20 Figure 1 is a face view of the plate; Fig. 2, a side edge view, and Fig. 3 a transverse section in the direction of the line $x x$ in Fig. 1.

Like letters of reference refer to like parts in the several views.

25 The improved plate is preferably made of sheet-zinc, and is adapted to the ordinary wash-board frame, to which it may be secured in the usual way, or otherwise. Transversely upon the face of the plate are a series of corrugations, A, Fig. 1, and on the side edges are formed crimps, as seen on one side at B, an edge view of which is shown in Fig. 2. This crimping of the side B is to take out the buckle and swell caused in shaping the plate 30 and to give a uniform edge to the plate for fitting into the side pieces. The conformation of the plate may be effected by either dies or rollers suitably formed and shaped for this purpose. Rollers are preferred, as this form 40 of plate can be made by rolling with facility without sufficient strain to break or crack the plate in passing through the rollers, which is a great saving and advantage to the wash-board.

45 It will be seen in Figs. 1 and 3 that the transverse corrugations or ridges partake of an angular form, the faces of which are broader than the depressions and parallel, or nearly

so, to each other. Upon the face of the ridges are a series of angular depressions from a to b , with projections or swells at c , and sloping down to b in the channel d , formed between the ridges or corrugations. These angular depressions a b and projections c are formed on the broadest surface of the ridges A, extending from f to g , while the narrow and depressed portion of the corrugations extends only from h to i , as shown in Figs. 1 and 2. Between the depressions a are swells or projections e , causing alternate depressions a and 50 projections e along the ridges A. It will be noted in Fig. 1 that the angular positions of the depressions a b and inclined sides thereof are in two diagonal directions in opposite lines, as indicated by the lines C C and D D. 55 There are also alternate projections or ridges and depressions longitudinally as well as transversely over the face of the board, as will be seen in Fig. 1. The depressions a are in a longitudinal line with the ridges at A 60 and projections e at the angle of depression a b . Hence there are a series of projections and angular depressions at right angles to each other across the plate and longitudinally. The corrugations across the board act upon the 65 clothes being rubbed in one direction only and uniformly. Conjointly therewith the oblique swells and depressions in the face of the corrugations act upon the clothes in a cross-wise direction, and by their peculiar shape 70 loosen up the articles being rubbed, so that the dirt is freely washed out by the water having free access to the article loosened up by the swells and depressions crossing the corrugations.

75 The plate for use is preferable in the position shown in Fig. 1, although the opposite side may be used. The swell and depression on the face in Fig. 1 show the reverse forms on the opposite side of the plate.

90 What I claim as my invention, and desire to secure by Letters Patent, is—

A metallic wash-board plate having a series of transverse angular corrugations, A, the faces of which are traversed by a series of 95 oblique or downward-diverging depressions,

a, with confluent upper ends, in the angle of which are projections or swells *c*, sloping down to the channels between the transverse corrugations, and having between the said series 5 of oblique depressions or grooves swells or projections *e*, causing alternating swells and depressions along in the face of said corrugations *A*, substantially as described.

In testimony whereof I affix my signature in presence of two witnesses.

MARSHALL H. FARNSWORTH.
